(57) **CLAIM**

The ornamental design for a combined plastic deep electrical junction box with a lighting module mounting yoke, as shown and described.

DESCRIPTION

FIG. 1 is a top view of a combined plastic deep electrical junction box with a lighting module mounting yoke removed and showing our new design;

FIG. 2 is a bottom view thereof;

FIG. 3 is a right side view thereof, the left side being identical;

FIG. 4 is a front view thereof, the rear view being identical;

FIG. 5 is a top perspective view thereof; and

FIG. 6 is a bottom perspective view thereof.

FIG. 7 is a bottom perspective view of a combined plastic deep electrical junction box with a lighting module mounting yoke shown in an alternate lowered position.

FIG. 8 is a bottom perspective view of a combined plastic deep electrical junction box with a lighting module mounting yoke shown in an alternate raised position; and

FIG. 9 is a bottom view thereof.

FIG. 10 is a bottom view of the lighting module mounting yoke with the plastic deep electrical junction box removed and showing our new design;

FIG. 11 is a top view thereof; and,

FIG. 12 is a top perspective view thereof.
